UNITED STATES PATENT OFFICE.

WILLIAM W. BIRNSTOCK, OF YORK, PENNSYLVANIA, ASSIGNOR TO YORK MILK MACHINERY COMPANY, OF YORK, PENNSYLVANIA, A CORPORATION OF PENNSYLVANIA.

BOTTLE CRATE.

Application filed January 8, 1924. Serial No. 685,037.

The present invention relates to improvements in bottle crates and more particularly to those of the class embodying a wooden case and metal cross strips which provide 5 longitudinal and transverse partition members forming individual cells for the bottles supported in the crate.

A primary object of the present invention is to provide novel and improved means for 10 attaching the ends of the longitudinal partition members to the ends of the crate, whereby such members of the partition will be held securely in place under a substantial tension which may be imposed upon them, and also the longitudinal partition members are accurately spaced relatively to one another, incident to the assembling of 15 the crate and are securely and permanently held in such relation. Another object of 20 the invention is to provide attaching means for the ends of the longitudinal partition members which will serve as reinforcements for the ends of the crate, they acting to resist splitting of the crate ends and to prevent 25 pulling apart of the crate ends when made in two or more pieces or when the crate ends become split from any cause.

To these and other ends, the invention consists in certain improvements and combinations and arrangement of parts all as will be hereinafter more fully described, the features of novelty being pointed out particularly in the claims at the end of the specification.

35 In the accompanying drawings:—

Figure 1 is a perspective view of a bottle crate constructed in accordance with the preferred embodiment of the invention;

Figure 2 is a top plan view of the crate 40 as shown in Figure 1;

Figure 3 represents a vertical section through one end of the crate, showing the improved means for attaching the ends of the longitudinal partition members to the 45 crate ends.

Figure 4 is a detail view, in section and on an enlarged scale, illustrating the partition attaching member, the mode of attachment of the partition members thereto and the 50 preferred mode of securing the attaching members to the crate end;

Figure 5 is a detail view of one of the partition attaching members as viewed from the left in Figure 4;

55 Figure 6 is a detail view, on an enlarged

scale, showing the preferred mode of attaching the ends of the transverse partition members to the sides of the crate;

Figure 7 is a detail view, on an enlarged scale and in perspective, illustrating a portion of the bottom structure of the crate;

Figure 8 is a top plan and Figure 9 is a view in elevation of a portion of the bottom rail or shoe of the crate; and

Figure 10 is a detail view of one of the 65 wires comprising the bottom structure shown.

Similar parts are designated by the same reference characters in the several views.

The present invention is applicable generally to bottle crates adapted to contain bottles of different kinds, although the invention is particularly applicable to crates of the kind used in the handling of milk bottles, such crates being used to contain the milk 70 bottles not only for shipment or distribution, but also while the bottles are being washed and otherwise handled in dairies, in consequence of which the crates are subjected to rough and severe usage. The preferred embodiment of the present invention which provides a crate of increased strength and durability, is shown in the accompanying drawings and will be hereinafter described 75 in detail. It is to be understood, however, that the invention is not restricted to the precise construction shown as equivalent constructions are contemplated and such will be included within the scope of the claims.

In the present instance, the crate comprises an outer case embodying sides 1 and ends 2, these parts being preferably constructed of wood, as is usual, the ends being provided at their inner sides with rabbets 3 in which the sides 1 are fitted so that the 80 sides will act as spacers to hold apart the ends in opposition to any tension tending to draw the ends toward one another. The sides and ends of the crate may be secured 85 together by nailing, as usual.

One or more partitions are employed for properly separating the bottles contained in the crate, two partitions in superposed relation being shown, for example, in the present instance. Each partition comprises longitudinal members 4 and transverse members 5, these members being composed preferably of strips of flat metal and the number used depends upon the number of bottles which are to be accommodated within the crate. 105 110

These partition members are arranged to intersect at a right angle and they may be interlaced as shown. The spaces between the intersecting partition members form the individual cells in which the bottles are to be contained.

The present invention provides novel and improved means for attaching and securing the ends of the longitudinal partition members 4 to the ends 2 of the crate, whereby these partition members are supported with greater security, they are capable of sustaining a substantial tension imposed thereon by the crate ends 2 and, moreover, the crate ends 10 are reinforced so that splitting thereof is resisted and pulling apart of the crate ends when composed of two or more pieces or in the event that they should become split, is prevented. Such attaching means comprises 15 preferably a plate 6 which may be composed of sheet metal of appropriate thickness or strength, the plate being stamped or otherwise formed so that it embodies a marginal or peripheral flange 7 which is adapted to 20 fit flatwise against the inner side of the crate end, and an inwardly bulged portion 8, the opposite side walls 9 of which converge toward an apex 10. The apex portion 10 of the plate is formed with a slot or opening 11 25 to receive the end of the respective longitudinal partition member, the portion of this partition member which extends into the chamber or cavity within the plate 6 having a perforation 12 which extends vertically therethrough, and the upper wall of the 30 plate 6 being provided with an opening 13 through which a pin or wire 14 may be inserted, so that this pin will enter and pass through the perforation 12 in the partition member. Where only one partition is used 35 in the crate, the plate 6 may be constructed to receive only a single partition member 4, but where, as shown in the present instance, a pair of partitions are used, the plate 6 is 40 constructed to receive the ends of the upper and lower longitudinal partition members. The attaching plate 6 is firmly secured to the 45 respective end 2 of the crate, it being preferable to employ rivets 15 for this purpose, is as shown, these rivets acting to securely fasten the marginal flange 7 of the attaching plate to the inner side of the crate end. It will be understood that one of these attaching plates will be provided for each end 50 of each longitudinal partition member or for the ends of each pair of superposed longitudinal partition members. In Figure 4 the end piece to which the attaching plate is secured is shown in one piece, whereas in Figure 3 the end shown is in two pieces, but in both instances the partition attaching plate will serve as a reinforcement or stay which will materially strengthen the crate end, it 55 resisting splitting and preventing pulling apart of the parts or pieces of the crate end 60 65

when made in two or more pieces, or, in the event that the crate end becomes split from any cause. The ends of the transverse partition members 5 are suitably secured in the sides 1 of the crate. For example, the ends 70 of these partition members may be perforated to receive nails 16 which may be driven into the pieces 1^a and 1^b which may be used in making up the crate sides, the pieces 1^a being of a width corresponding with the desired vertical spacing of the two partitions, when such are used.

In assembling a crate provided with partition securing means as hereinbefore described, the perforated ends of the longitudinal partition members 4 are inserted through the slots 11 in the attaching plates 6, which latter have been previously secured to the inner sides of the crate ends, and the pins 14 are inserted through the openings 13 and through the perforations 12 in the inserted ends of the partition members. The crate ends 2 are then drawn apart in the manner usual in the assembling of crates of this class, and while the crate ends are thus held apart, the crate sides are put in place and secured. As the crate ends are drawn apart and tension in consequence is applied to the longitudinal partition members 4, the pins 14 will be drawn toward or into the apex of the respective attaching plate 6, the inwardly converging walls 9 of the attaching plate acting to properly center the pin 14, and hence the longitudinal partition members 4 will be accurately spaced apart 90 as an incident in the assembling of the crate. The insertion of the crate sides 1, while the crate ends are drawn apart so as to impose tension on the partition members 4, serves to maintain the tension on the partition members 4 so that the partitions are securely supported within the crate and sagging of the partitions is avoided.

Any suitable bottom structure may be used to support the bottles in the crate. In the present instance, a number of individual wires 17 are used, these wires being spaced apart at suitable intervals and extending longitudinally between the crate ends 2. Each wire has eyes or loops 18 formed at its ends which are engaged and secured by nails 19 which directly engage within them. The crate ends are preferably provided with separate bottom strips or shoes 20 having recesses 21 formed in their upper faces to receive and accommodate the eyes or loops on the ends of the respective bottom wires. The nails 19 may be driven upwardly through the bottom strips into the crate ends, so that they will serve to secure the bottom strips in place as well as to engage and secure the eyes or loops 18 on the ends of the bottom wires 17. The bottom strips or shoes 20 are preferably drawn apart during 100 105 110 115 120 125 130

the assembling of the crate in order to impose longitudinal tension on the bottom wires. The wires 17 comprising the bottom of the crate may be reinforced by a suitable 5 number of transverse stays 22, a pair of stays being shown in the present instance which are like those shown and described in my prior Patent No. 1,324,580, granted December 9, 1919, the end of each reinforcement 10 being accommodated in a recess 23 in the respective side of the crate and secured in place by a nail 24 which may be driven upwardly from the lower edge of the crate side through a perforation 15 formed in the end of the transverse reinforcement.

I claim as my invention:—

1. A bottle crate comprising ends, partition members extending between said ends, 20 attaching members secured to the inner faces of the ends and into which the terminals of the partition members extend, and securing members insertable into the attaching members, said securing members being connected 25 under tension to said partition members and sustaining longitudinal tension thereon.

2. A bottle crate comprising ends, partitions arranged in superposed relation therein and embodying superposed members extending between said ends, and attaching members secured to the inner sides of said ends, each attaching member being arranged 30 to extend vertically on the respective crate end and adapted to receive the ends of members of the superposed partitions, and a 35 common securing member at the inner side of the respective end of the crate and bearing against the respective attaching member for fastening said superposed members of 40 the partition to the respective attaching member.

3. A bottle crate comprising ends, partition members extending between said ends, and attaching members secured to the inner 45 sides of the crate ends for connecting the ends of said partition members thereto, said attaching members having convergent walls and securing means for the partition members which bears against and is centered by 50 said convergent walls under tension applied to the partition members to space the latter.

4. An attaching member for securing a partition member in a bottle crate comprising a plate having means for securing it to a wall of the crate and adapted to receive an 55 end of the partition member, and a locking pin extending through the end of the partition member and bearing against said plate for securing the partition member to the attaching member. 60

5. Means for securing the apertured end of a partition member to the wall of a crate comprising a plate having means for securing it to the wall of the crate and provided with a portion which is offset inwardly from 65 said wall, said offset portion being slotted to receive the apertured end of the partition member, and a pin insertable at the outer side of the offset portion of the plate and through the aperture in the partition 70 member.

6. An attaching member of the character described comprising a recessed portion into which an apertured partition member is insertable, and a pin insertable into the recessed portion of the attaching member and into the aperture of the partition member. 75

7. A device for securing a partition member to a wall of a crate comprising a plate adapted to be secured to said wall and having a recessed portion which is slotted to receive the end of the partition member and provided with convergent walls, and a pin insertable into the recessed portion of the plate to engage the end of the partition 80 member therein, the pin being positioned by said convergent walls. 85

8. An attaching plate for securing the apertured end of a partition member to a wall of a crate, said plate having a marginal 90 portion adapted to be secured to said wall and a portion which is bulged away from said wall and slotted to receive the end of the partition member, the opposite sides of the bulged portion of the plate being convergent, and a pin insertable into the bulged portion of the plate between the convergent 95 sides thereof and into the aperture in the end of the partition member.

In testimony whereof I have hereunto set 100 my hand.

WILLIAM W. BIRNSTOCK.
